UNITED STATES PATENT OFFICE

2,030,916

DOOR FASTENER

James C. Gard, Bloomington, Ill.

Application April 13, 1934, Serial No. 720,385

1 Claim. (Cl. 292—269)

This invention has reference to door fastenings, particularly to a fastening device capable of acting as a door or window lock or as an adjustable fastening as will be explained.

5 An object of the invention is to provide a device suitable for attachment to doors, hinged windows and the like capable of securely locking the same in closed position or acting as a guard lock whereby the door or window may be opened part way to 10 permit communication or ventilation without danger of intrusion by outsiders.

Another object is to provide a device as noted, attachable to any door or window by simple means which is substantially invisible when in closed 15 position.

A further object is to provide a device of the class described which is simple, rugged and of handsome appearance.

Other objects will appear in the following description and accompanying drawing, in which—

Fig. 1 is a side elevational view of my device as the same would appear when attached to a door frame and as viewed from the right, in Fig. 2, with certain portions broken away to permit clear view 25 of underlying parts and a dotted outline showing the mechanism in operated position;

Fig. 2 is an edge elevational view of the same showing a fragmented portion of a door which carries a portion of the device as will be described;

30 Fig. 3 is a sectional plan or top view taken from line 3—3 in Fig. 1;

Fig. 4 is an elevational view taken from the side opposite that shown in Fig. 1 as noted by arrows 4—4 in Fig. 2;

35 Fig. 5 is a sectional view, showing parts to be described, taken from line 5—5 in Fig. 1; and

Fig. 6 is a fragmental perspective detail view showing a portion of the mechanism to be described.

40 Referring to the drawing, it is to be noted that my device consists generally of two co-operating mechanisms, one to be attached to a door jamb, the other to be attached to the door.

Figs. 1 and 2 disclose the assembly as comprising a mortised plate member 10 secured to a door jamb 10—A by means of screws 11.

In the mortised portion of plate 10, between the door jamb and plate is fitted a link member 12, the same having an arcuately fashioned slot 13 50 formed in its lower portion.

Slot 13 is so proportioned as to slidably receive a rivet 14 which is secured in plate 10 as best shown in Fig. 2, the edges of the slot being mortised to clear a portion of the head of the rivet as 55 shown.

In the upper portion of plate 10 is a recess 15 so disposed as to receive an extending, similarly formed portion 16 near and integral with the upper end of link 12. The upper edge of the link is provided with a recess 17 adapted to receive the 5 lower end of a bar member 18 which is slidably mounted within a mortise formed in the upper portion of plate 10.

A recess 19, formed in the bar engages a tooth portion 20 of a rocking member 21 pivotally supported in plate 10. A small finger member 21' extends beyond the edge of plate 10 and provides means whereby member 21 may be manipulated to slide the bar 18 vertically to engage it in the recess 17, to securely lock the link in the position 15 shown in solid lines in Fig. 1, or to release it to permit movement of the link as shown in dotted lines.

A slotted opening 22 is disposed in link 12 as shown in the several views. A mortised area 23 surrounds the slot on the inner surface of the link.

Opposite the slot 22, secured in an adjacent door or window 24—A as shown in Figs. 2 and 3, is a bolt mechanism comprising a casing 24 within which is a sliding bolt member 25 provided with a 25 rack portion 26.

Projecting through the body of the door and casing 24 is a pinion member 27 disposed as shown in Fig. 3 with the pinion in mesh with rack 26.

Secured to the extending end of the pinion is a 30 knob 28 by means of which the pinion may be rotated to propel the bolt 25 outwardly to engage link 12 as indicated in Fig. 2 or to withdraw it into casing 24 out of co-operative position.

The pinion-knob unit is retained in proper position on the door by means of a surface plate 29 secured to the door by screws 30.

Fig. 6 illustrates that bolt 25 is provided, at its outer end, with an oblong head 31 connected to the body portion of bolt 25 by a neck portion 32.

Bearing in mind that slot 22 is so proportioned that the bolt head 31 and neck 32 are freely movable therein, it will be apparent that, with the several parts arranged as in Figs. 1, 2, and 4, 45 knob 28 may be manipulated to insert or withdraw the bolt head from engagement with the link. If, with the bolt in inserted position, the bar 18 is moved into engagement in recess 17, as in Fig. 4, the door 24—A will be securely locked in closed 50 position.

In case it is desired to unlock the door so that it may be opened to a limited extent while at the same time retaining an effective connection between the door and jamb, the finger 21' may be 55

manipulated to disengage bar 18 and thus render the link free to move into the position shown in dotted lines in Fig. 1, and in Fig. 3, wherein the door has been opened to the extent permitted by 5 the link.

The movement described is made possible due to the sliding and pivotal movement of the link on rivet 14 and pivotal movement of the link on bolt 25.

10 With the door in ajar position, separation of the link from the door is prevented by means of the lip portion of the head 31 of bolt 25 engaging behind the walls of slot 22 as indicated in dotted lines in Fig. 1 and in Fig. 3.

15 The latter locked relation is obviously brought about by the angular position of link 12 relative to the bolt head 31.

Due to the changes in angular relation between the several parts mentioned, it is necessary that 20 the parts have a certain amount of freedom of movement in substantially all directions, hence the mortised edges of slot 13 and a loose fitting between head 31, neck 32 and slot 22 are provided.

25 When it is desired to use the door in the conventional manner, the door is first closed to place the parts as in Figs. 1 and 4, lower the bar 18 to

lock the link as described and finally withdraw the bolt 25 by the means described whereupon the link is held neatly assembled with plate 10 and there being no connection between the door and link the door may be opened and closed in the usual 5 manner.

With the foregoing in mind, it will be apparent that a door or window fitted with my device may be securely locked in closed position, held ajar in locked relation or used in the conventional man- 10 ner.

What I claim is:

A device of the class described including a plate member attachable to a door frame, a link member mounted for pivotal and longitudinal 15 movement on said plate and disposed between the plate and door frame, a locking bar mounted for sliding movement on said plate above the said link, a recess in the upper end of the link adapted to receive said bar in locking relation to prevent pivotal movement of the link, a lug portion disposed on the side of said link and a recess in said plate adapted to receive said lug portion in a manner to hold said link against longitudinal movement, and mechanism secured in the door 20 movable to engage or disengage said link.

JAMES C. GARD.
